UNITED STATES PATENT OFFICE.

RAYMOND U. BUNKER, OF YONKERS, NEW YORK.

METHOD OF EVAPORATING AQUEOUS SOLUTIONS.

1,221,022.

Specification of Letters Patent. Patented Apr. 3, 1917.

Application filed December 8, 1913. Serial No. 805,372.

To all whom it may concern:

Be it known that I, RAYMOND U. BUNKER, a citizen of the United States, residing at Yonkers, county of Westchester, and State of New York, have invented certain new and useful Improvements in Methods of Evaporating Aqueous Solutions, of which the following is a clear, full, and exact description:

10 This invention relates to methods of evaporating aqueous solutions such as those of sugar, salt, etc., and more particularly to a multiple effect continuous graining pan. If on the principle of evaporation in multiple effect the concentration of sugar solutions, for instance, is carried beyond the point where crystals develop, trouble is encountered. In such a case some of the crystals are always left behind in each body or 15 chamber as the liquor advances through the apparatus. Those crystals which remain too long in any one body or chamber grow unduly large, "smear" develops and a conglomerate mass results which, on being released to the atmosphere, resembles "concrete". Whenever a handsome uniform grain, termed by the trade "granulated" sugar, is desired the single effect or intermittent vacuum pan has been found necessary.

By means of the method forming the subject of the present invention, uniform crystals of suitable appearance and hardness may be produced continuously in multiple effect, with consequent saving in heat and labor over the present method of using single effect vacuum pans only. By the use of the described new method, clean crystals will be produced and the final concentration of all sugar solutions for instance, will be effectuated with the same heat economy as effected in the well-known multiple effect evaporator in treating the solutions.

Another object of the invention is to provide practical and efficient means for graining sugar, salt, etc.

These being among the general objects of the invention, the same consists of certain steps in the method, to be hereinafter described and then pointed out in the claims with reference to the accompanying drawings illustrating a suitable embodiment of an apparatus for carrying out the invention, and in which—

55 Figure 1 is a front elevation of a multiple

effect continuous graining pan, embodying the invention;

Fig. 2 is a plan view of the same parts, showing in addition a liquor supply tank;

Fig. 3 is a side elevation of the chambered body which is shown next to that at the left-hand end of Fig. 1;

Fig. 4 is a view partly in plan, and partly in section on the line 4—4 Fig. 3; and

Fig. 5 is an enlarged vertical section on the line 5—5 Fig. 4, showing the interior of one of the bodies.

Referring to the drawings, a plurality of chambered bodies 10, 11, 12 and 13 are shown; in the present instance, four. The general construction of these bodies is well-known, but certain improvements have been added thereto by the present invention. Each of said chambered bodies 10, 11, 12 and 13 is divided in its lower portion into a number of pockets, such as 14, 14^a, 14^b and 14^c, which are shown in connection with the chambered body 11. These pockets are indicated in broken lines in Fig. 2 but can be seen more clearly in Fig. 4 from which it will be seen that said pockets are separated by transverse upright walls 15. These walls extend from the bottom of each chambered body toward the top of the same but are separated from the top by a transverse space 15^a which is in the upper part of each body in common with all of the pockets therein. In the lower part of each pocket is a heater or calandria 16, so that each pocket has its own heater. These heaters may, when expedient, be constructed with tubes like boiler tubes so as to permit of the desired ebullition of the contents of the pockets. For the purpose of withdrawing condensed vapors, the said heaters are provided with discharge pipes 17, 18. The said pockets may be said to correspond with a plurality of pans each having its separate heater and other accessories, and the said pans having a common vapor space comparable with the space 15^a above mentioned.

Having now described the general construction of the chambered bodies and the parts in them, the new arrangement of the bodies will be explained. In multiple effect continuous evaporators heretofore in use, the syrup or liquor is advanced from the chambered body of the highest temperature and lowest vacuum to the next following bodies of gradually decreasing temperatures and

increasing vacuums, or, permitting the vapors to take the same course as above, the liquor is passed through the apparatus in reverse direction. The plan of the present invention is to divide up the work of concentration approximately from 58° to 95° Brix into a multiple number of stages. In general, four stages would be convenient, as is the case in the preliminary concentration, and consequently the four bodies before referred to are shown. Under the present invention the material to be concentrated, as for instance massecuite, is advanced not step by step with the vapors, but to that body in which a suitable temperature offers to best carry on the next stage in graining or crystallization. Thus "boil down" in the coolest body 10, in which the material to be concentrated may have a temperature of 135° F. and the body 23" of vacuum, this body 10 being the last body or that nearest the condenser 10*. Next, transfer the supersaturated solution to the second chambered body 11, in which the material to be concentrated 25 may have the higher temperature of 175° F. and said body the lower vacuum of 10", to induce crystallization. Next, transfer the material, as massecuite, to the first or hottest body 12, into the heater of which live or exhaust steam is admitted so that the material to be concentrated may have a temperature of 185° F., and said body may have a lower vacuum of 5". In the body 12 the grain is "baked in" at a high temperature to prevent 35 "smear." Lastly, transfer the material to be concentrated, as massecuite, to the chambered body 13 in which the material to be concentrated may be a temperature of 160° F., and said body a vacuum of 18".

40 For convenience in the transference of the sugar solution and massecuite, the bodies 10, 11, 12 and 13 are lined up in the order of progression of the sugars and suitable temperatures are arrived at in any one body, not 45 by bringing the vapors from the next body adjacent but possibly from the second or third distant body. The apparatus whereby this method of working may be carried out will now be further described. Each of the 50 pockets of the chambered body 11 is provided, below the latter, with a connection 19, by means of which a batch may be admitted into and discharged from the particular pocket having said connection. Each of the 55 other bodies 11, 12 and 13 have corresponding connections 19*, 19^b and 19^c, respectively. Certain branches of each of said connections are connected with suitable charge pipes 21, 21^a, 21^b and 21^c which may lead from a sugar 60 liquor tank 23. Means are provided for connecting the charge pipes 21 and so on with any particular pocket of any one of the chambered bodies. To this end the charge pipes are connected with manifolds 22, 22^a, 22^b and 22^c and the manifolds are connected by valves 20, 20^a, 20^b and 20^c with the connections such as 19. The valves 20, 20^a, 20^b and 20^c may be opened and closed by means of suitable mechanisms, through the medium of hand-rotated shafts 45. It will therefore be seen that the charges of sugar or other liquor to the pockets in the chambered bodies are so controlled by the said valve mechanism that each pocket may be charged independently of any other 75 pocket.

Between adjacent bodies 10, 11, 12 and 13 are located pumps 27 for the purpose of pumping the massecuite from body to body. To permit this, the said connections, such as 19 are adapted to discharge downwardly 80 through foot-valves 24, and the connections 19^a through foot-valves 24^a. The foot-valves 24, and all valves corresponding therewith, are controlled separately by means of hand-rotated shafts 46, and the said valves are connected to a manifold 47 for each body 10 and so on, which manifolds are in turn connected with pipes, as 25, leading to the pumps, from which pipes 25^a lead. The 85 pipes 25^a lead to manifolds, as 48, which in turn are connected to the connections of the bodies 11, 12 and 13, by charging valves such as 26 for the second chambered body 11. It will therefore be understood that the chambered bodies 10, 11, 12 and 13 are provided 90 with corresponding charging valves such as 20 for independently controlling an inlet of sugar liquor; for instance, to each pocket such as 14; they are also provided with corresponding foot-valves such as 24 for controlling the discharge of massecuite, for instance, from each pocket independently; and the bodies 11, 12 and 13 are provided with corresponding charging valves such as 26 for 95 controlling the inlet of massecuite independently into each of the pockets of said bodies, 100 from the body which is in advance.

105 A steam supply manifold 28 is by means of vapor valves 29 connected with the pockets of the chambered body 12 so that the separate heaters of said pockets such as 16 may be supplied separately with steam. The flow of the vapors from the chambered body 12 and through the series of bodies 115 is as follows: From the body 12 to the body 11, through the medium of a vapor pipe 30 connected with a manifold 31, which is connected separately with the pockets in the body 11 by means of vapor valves 32 connected 120 with the heaters in the separate pockets. From chambered body 11 the vapors pass by means of a vapor pipe 34 to a manifold 35 which is connected to the separate pockets of the chambered body 13 125 by means of vapor valves 36. Finally the vapors pass from the chambered body 13 through a vapor pipe 37 which leads over to a manifold 38 for the first body 10, said manifold being connected by means of 130

vapor valves 39 and pipes 40, within the pockets of the body 10, with the pocket heaters such as 16. Similar connections such as 40 lead the vapors to each heater of all of the bodies 10, 11, 12 and 13.

It will therefore be seen that the vapors from one chambered body to the next and so on pass in one sequence and that the massecuite, for instance, may be advanced 10 from body to body in a different sequence, but not successively or in numerical sequence along the bodies as a liquid, as will now appear more clearly. The method is carried out as follows: In the first instance 15 sugar liquor, for instance, is admitted to the series of pockets of each body 10, 11, 12 and 13, the quantity being under control of the charging valves such as those at 20. The advance of the massecuite through the 20 series of chambered bodies is controlled (the valves such as at 20 being closed) by means of the pumps between the bodies and the valved connections before described. It will be seen therefore that the massecuite 25 may be advanced from the coolest body 10 to the next body 11 of most suitable temperature and vacuum; from the body 11 to the body 12 of the next most suitable temperature, and finally to the body 13. The 30 course of the vapors proceeds in a different series of steps, that is to say from the heater of body 12, of highest temperature and lowest vacuum, to the heaters of bodies 11, 13 and 10, of gradually decreasing temperatures and gradually increasing vacuums.

As regards the pockets of the different chambered bodies and the utility of the same, the method of procedure is as follows: A complete transference of all growing 40 crystals of like age in one batch may be effectuated from body to body without disturbing the vacuum in any given body, and this is particularly desirable where each body has pockets, as all the pockets 45 in each body have a common vapor space but separate heaters. By this means concentration may be carried forward as far as is desirable in a given pocket. Then the 50 contents of that pocket may be withdrawn by a suitable regulation of the described valve mechanism and the pump (or by a barometric column) and introduced into the next body. The pocket thus left vacant may be thoroughly cleansed with hot water 55 in well known manner until all remaining crystals are dissolved. The withdrawal above mentioned may be accomplished without in any way disturbing the continuous operation of the apparatus as a 60 whole. Batches of massecuite may also be advanced from body to body by means of the proper valves and the pockets and at the same time fresh charges of liquor or syrup at or about 58° Brix may be introduced 65 into any body in order to promote

the proper growth of crystals, just as is done in any single effect pan. Each pocket should preferably have a well-known proof-stick, such as 50, so that the material being concentrated may be tested.

It is obvious that the invention is susceptible of a wide range of modification, as parts of the apparatus illustrated may be omitted, parts added and parts substituted without departing from the invention resident in the described method.

What I claim as new is:—

1. The method of evaporating aqueous solutions in a series of vacuum chambers of varying temperatures, which consists in first 30 boiling down the material to be concentrated, as, for instance, massecuite, in the coolest chamber, next boiling it in a second chamber at a higher temperature, then boiling it in a third chamber at still higher 35 temperature, and finally boiling it in a fourth chamber, the said relation of said chambers being out of relation to the progression of vapors, and in which fourth chamber the temperature is lower than in 40 the chamber preceding it.

2. The method of evaporating aqueous solutions in a multiple effect continuous graining pan, which consists in boiling down charges of the material to be concentrated, 45 for instance, massecuite, in the various chambers at different temperatures, passing the vapors step by step through the series of chambers, and advancing the charge from one chamber into another but into that chamber which is at the temperature to which the charge should be subjected for further concentration depending upon the existing stage of its evaporation, said vapors being passed through the chambers in such way that the 50 last of said series of chambers in the order of advance of the charge is in a different relation to the order of progression of the vapors.

3. The method of evaporating aqueous solutions in a series of vacuum chambers of varying temperatures and vacuums, which consists in first boiling down the material to be concentrated, as for instance massecuite, in the coolest chamber, next, boiling 115 it in a second chamber at a higher temperature and lower vacuum, then boiling it in a third chamber at still higher temperature and still lower vacuum, finally, boiling it in a fourth chamber in which the temperature 120 is different from that of said third chamber, and passing the vapors through the series in such way that said fourth chamber is next to the last in the order of progression of vapors.

4. The method of evaporating aqueous solutions in a series of vacuum chambers, each of which is divided into a number of pockets having a vapor space in common, which consists in boiling the material to be concen- 130

trated, as for instance, massecuite, in separate batches in said pockets, conveying together the vapors passing off during ebullition, from the vapor space of one chamber 5 to that of another chamber, and transferring the material to be concentrated as frequently as desired from one or the other of said pockets in one chamber to one or the other of the pockets of another chamber when the 10 concentration is carried forward still farther, whereby the vacuum in any chamber is not disturbed.

5. The method of evaporating aqueous solutions in a series of vacuum chambers, each 15 of which is divided into a number of pockets having a vapor space in common, which consists in charging any number of said pockets with liquor or syrup, then emptying a pocket

of a second chamber of its charge of material to be concentrated, as massecuite, and 20 transferring the same to the appropriate pocket of a third chamber, and then transferring the advancing material from a pocket of a first chamber to said emptied pocket of said second chamber, and repeating this procedure as to any of the pockets 25 of the chambers without disturbing the contents of the pockets not involved in such transfer.

Signed at New York city, New York this 30
3d day of December, 1913.
